UNITED STATES PATENT OFFICE

2,341,852

WATER HEATER

George D. Arnold, Peru, Ind.

Application October 13, 1942, Serial No. 461,863

3 Claims. (Cl. 122—159)

The present invention relates to new and useful improvements in water heaters, and has for its primary object to provide an insulated casing substantially in the form of a stand boiler and having a combustion chamber surrounded by inner and outer communicating water jackets and arranged to receive cold water in the outer water jacket for circulation downwardly into the inner water jacket and upwardly in the latter for discharge from the top thereof.

A further object in this construction is to provide a water heater that will give complete circulation due to the separate path ways of the cold and hot water which will result in the elimination of condensation on the surface of the combustion chamber as well as eliminate the formation of lime and scale, due to the water moving rapidly through the entire heater at a temperature above the temperature of the incoming water regardless of the fact that heat would not be applied to the surface.

A further object is to provide a water heater of this character of simple and practical construction, which is efficient and economical in use and otherwise well adapted for the purposes for which the same is intended.

Other objects and advantages reside in the details of construction as more fully hereinafter described and claimed, reference being had to the accompanying drawings forming part hereof, wherein like numerals refer to like parts throughout and in which:

Figure 1 is a vertical sectional view, and

Figures 2 and 3 are transverse sectional views taken, respectively, on the lines 2—2 and 3—3 of Figure 1.

Referring to the drawings in detail, wherein, for the purpose of illustration, I have disclosed a preferred embodiment of the invention, the numeral 5 designates a cylindrical casing supported on legs 6 and having a water jacket 7 positioned therein and spaced from the walls of the casing 5 to provide an insulation chamber in which insulation material 8 of conventional form may be placed.

The lower portion of the jacket 7 is formed with an outer cylindrical wall 9, an inner cylindrical wall 10, and an intermediate cylindrical wall 11 supported in spaced concentric relation by means of the rivets or bolts 12.

The lower edges of the walls 9 and 10 rest on the bottom 13 of the casing 5 and the lower edge of the intermediate wall 11 terminates above the bottom 13, as shown to advantage in Figure 1 of the drawings.

The top of the inner wall 10 is closed by a top plate 14 to form a combustion chamber 15 in the bottom of which is positioned a fire pot 16 of refractory material supported on a plate 17 which forms the central portion of the bottom of the casing 5 and which is removably secured therein by means of the lugs 18. A burner 19 of conventional construction is positioned in the fire pot 16 and may be in the form of a gas burner, as shown in the drawings, or may comprise an oil burner or solid fuel heater, if desired.

Spaced above the top plate 14 is a water plate 20 which closes the top of the intermediate wall 11 and spaced above the water plate 20 is a top plate 21 for the outer wall 9 of the water jacket.

The water plate 20 is formed with a central opening 22 having an upstanding flange 23 and rising from the central portion of the plate 21 is a reduced chamber 24 disposed immediately above the opening 22 of the water plate 20.

Surrounding the chamber 24 is an upper combustion chamber 25 which is spaced from the top of the chamber 24 as well as from the sides thereof and leading from the chamber 25 is a stack 26 extending through the top of the casing 5.

A water inlet pipe 27 extends into the outer wall 9 of the water jacket at a point immediately above the water plate 20, and water is admitted to the water jacket where the heat from the burner causes the water to circulate in a manner as indicated by the arrows in Figure 1 of the drawings. The water is withdrawn from the top of the water chamber 24 by a pipe 28 and may lead to an auxiliary storage tank, if desired.

A drain pipe 29 enters the casing at the lower portion of the water jacket.

The upper combustion chamber 25 is connected to the lower combustion chamber 15 by means of a plurality of tubes 30 extending through the plates 14, 20 and 21.

It is believed the details of construction and manner of operation of the heater will be readily understood from the foregoing without further detailed explanation.

What is claimed is:

1. A water heater comprising a casing, a lower water jacket in the casing in spaced relation to the walls thereof, said jacket including an outer wall, an inner wall and an intermediate wall, said inner and outer walls extending to the bottom of the casing and said intermediate wall being supported with its bottom edge above the bottom edges of the inner and outer walls, top plates at the upper edges of each of said walls, and vertically spaced apart, said top plate of the inter-

mediate wall having an opening, a reduced upper water chamber rising from the uppermost top plate open at its bottom and having communication with the lower water jacket, a stack rising from the intermediate plate at the opening therein and terminating adjacent the open bottom of the upper water chamber, a water supply pipe connected to the lower water jacket immediately below the uppermost top plate, a water discharge pipe connected to the upper water chamber, internal heating means for the lower water jacket, and external heating means for the upper water chamber.

2. A water heater comprising a casing, a lower water jacket in the casing in spaced relation to the walls thereof, said jacket including an outer wall, an inner wall and an intermediate wall, said inner and outer walls extending to the bottom of the casing and said intermediate wall being supported with its bottom edge above the bottom edges of the inner and outer walls, top plates at the upper edges of each of said walls, and vertically spaced apart, said top plate of the intermediate wall having an opening, a reduced upper water chamber rising from the uppermost top plate open at its bottom and having communication with the lower water jacket, a stack rising from the intermediate plate at the opening therein and terminating adjacent the open bottom of the upper water chamber, a water supply pipe connected to the lower water jacket immediately below the uppermost top plate, a water discharge pipe connected to the upper water chamber, a heating chamber surrounding the upper water

chamber, a combustion chamber centrally of the water jacket, and discharge tubes leading from the combustion chamber through the top plates of the water jacket and communicating with the heating chamber for the upper water chamber.

- 5 3. A water heater comprising a casing, a lower water jacket in the casing in spaced relation to the walls thereof, said jacket including an outer wall, an inner wall and an intermediate wall, said inner and outer walls extending to the bottom of the casing and said intermediate wall being supported with its bottom edge above the bottom edges of the inner and outer walls, horizontal plates closing the upper end of the water jacket and including an upper plate, an intermediate plate and a lower plate connected, respectively, to the outer, intermediate and inner walls, said intermediate plate having an opening, a dome rising from the upper plate having open communication with the lower water jacket and forming a reduced upper water chamber rising from the upper plate, a stack rising from the intermediate plate at the opening thereof and terminating adjacent the bottom of the dome, a water supply pipe connected to the lower water jacket at a point between the upper and intermediate plates, a water discharge pipe connected to the upper water chamber, a heating chamber surrounding the upper water chamber, a combustion chamber within the lower water jacket, and tubes connecting the heating chamber with the combustion chamber.

GEORGE D. ARNOLD.
